UNITED STATES PATENT OFFICE.

CHARLES E. GERVAIS, OF NEW YORK, N. Y., ASSIGNOR OF ONE-HALF TO
WILLIAM S. JESSUP, OF SAME PLACE.

LAMP.

SPECIFICATION forming part of Letters Patent No. 678,655, dated July 16, 1901.

Application filed December 8, 1900. Serial No. 39,160. (No model.)

To all whom it may concern:

Be it known that I, CHARLES E. GERVAIS, a citizen of the United States, and a resident of the city of New York, borough of Manhattan, in the county and State of New York, have invented a new and useful Improvement in Lamps, of which the following is a full, clear, and exact description.

One purpose of the invention is to provide a lamp adapted to burn oil or other inflammable fluid and to use an electric battery in connection with the lamp, the battery being so connected with the lamp that a heat or resistance coil may be made to ignite a primary wick, the flame of which will be instantly communicated to the illuminating-wick, and to provide means whereby as soon as the illuminating-wick is ignited the current from the battery may be broken and the flame at the primary wick automatically extinguished.

A further purpose of the invention is to provide means for normally holding the zinc element of the battery out through the exciting fluid and to quickly bring the zinc element in coaction with the carbon elements of the battery.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the improved lamp. Fig. 2 is a vertical section through the lamp, taken practically on the line 22 of Fig. 4, showing the extinguisher removed from the heat or resistance coil. Fig. 3 is a side elevation of the upper portion of the lamp when the lamp is in operation, and Fig. 5 is a horizontal section taken practically on the line 55 of Fig. 2.

A represents a receptacle adapted to contain an exciting fluid, and the said receptacle is provided with a neck 10, upon which neck a metal collar 11 is screwed or otherwise secured. A disk or strip 12 of a non-conducting material is located in engagement with the inner face of the upper portion of the said cap 11, and a metal plug 13 is held in the

upper portion of the cap in any suitable or approved manner, the upper face of the plug being in engagement with the aforesaid insulating material 12.

Two carbons 14 are secured in any suitable or approved manner to the plug 13, and these carbons extend down into the exciting fluid contained in the receptacle A, as shown in Fig. 2. The position of the carbons relative to each other is illustrated in Fig. 5. The plug 13 is provided with an opening 15, extending through it and through the upper portion of the cap 11 and the non-conducting disk or strip 12. One manner of holding the plug in position is shown in Fig. 2, in which a rod 16 of metal is passed through suitable registering openings in the upper portion of the cap and in the insulating material 12 and the plug 13, a nut 17 being screwed upon the inner end of the rod 16 to an engagement with the under face of the plug 13. This rod 16 is provided with an enlargement 18 at its upper end, and in this enlarged portion of the rod a horizontal opening 19 is made, and a binding-screw 20 is passed through the upper part of the enlargement into the said opening, as is also shown in Fig. 2.

A head B is located upon the cap 11, and this head B consists of a horizontal base member b, an upper tubular member b', and a vertical connecting member b². At one portion of the base member b of the head B an upwardly-extending tube 21 is located over an opening in the said base or lower member b, which opening is in registry with the opening 15 in the plug 13. The upright member b² of the head is provided with a longitudinal bore, through which the rod 16 passes, and a chamber is formed in the upper tubular member b' of the head immediately over the connecting member b², in which chamber the enlargement 18 of the said rod is seated; but between the enlargement 18 of the rod 16 and the bottom of the said chamber a strip of insulating material is located, as is shown in Fig. 2.

A lever 22 is fulcrumed at the upper portion of the tubular upper member b' of the head B, and this lever carries an extinguishing-cap 22^a. At the pivot-point of the lever 22 an arm 23 is secured, and this arm is con-

nected by a link 24 with the upper portion of a rod 25, which rod is free to move in the tube 21 and passes into the receptacle A through the opening 15 in the plug. A zinc plate 28 is secured to the lower end of this rod 25, and the said zinc plate is located between the carbons 14 and is held out of contact with both carbons preferably by a carbon plug 29, which extends through the upper portion of the zinc plate and beyond the sides thereof, the said plug engaging with the carbon elements 14 of the battery thus formed.

Normally the zinc plate 28 is held within the upper portion of the receptacle A at a point above the exciting fluid in said receptacle, and the zinc element 28 is held in this position preferably through the medium of a spring 27, which is coiled around the tube 21 and bears against a knob 26 at the upper end 20 of the battery-rod 25, and the lower end of the spring has bearing on the bottom of the base member *b* of the head B. When the battery-rod 25 is pressed downward, the spring 27 is brought under tension and the zinc element 28 is brought into the exciting fluid of the battery and the battery will be in action. At this time the extinguishing-cap 22^a will be raised to the position shown in Fig. 2; but when the battery-rod 25 is relieved from pressure and the zinc element is carried out of the exciting fluid the extinguishing-cap will be brought to the horizontal position shown in Figs. 1 and 3.

The upper tubular member of the head B is longitudinally cut from the seat in which the enlargement of the rod 16 is placed, and a clamping-pin 30 is passed through suitable openings in the upper portion of the said upper member *b'* of the head B, so as to draw 40 the separate portions of the said member together and clamp said member upon an object which may be introduced therein.

A lamp C is used in connection with the battery which has just been described. This 45 lamp may be of any size and may be of any material. It is shown provided with an exteriorly-threaded neck 31, which receives a threaded collar 32, the said collar forming a portion of a block 33, and this block is provided with a cylindrical extension 34, adapted to enter the bore or main chamber in the upper member *b'* of the head B. In this manner 50 a slip connection is obtained between the support for the lamp and the head B, carried by the battery.

A tube 35, of non-conducting material, extends longitudinally through the extension 34 to its inner end and up and out through the top of the block 33, as is shown best in Fig. 2. 55 A wire 36 is carried through the insulating-tube 35 and is held in the enlargement 18 of the rod 16 by the binding-screw 20, as is also shown in Fig. 2. The end of the wire 36 which passes out through the upper outer end of the insulating-tube 35 is connected with a heat or resistance coil 37, made of platinum wire, and this coil is likewise connected with a rod

or tube 39, which is secured in any approved manner in the block 33.

A tube 40 is passed through the block 33, and this tube 40 is adapted to receive a wick 41 for illuminating purposes. Adjacent to the tube 40 an opening is made in the block just below the heat or resistance coil 37, and the upper end of a larger wick 42 is passed through this opening, the larger wick being what I term a "primary" wick, since when the circuit is completed this primary wick 42 is ignited and the flame from this primary wick will ignite the illuminating-wick 41. This ignition takes place when the battery-rod 25 is pushed downward and the zinc element is carried into the exciting fluid. At this time the extinguishing-cap 22^a is raised, as shown in Fig. 2; but the moment that the battery-rod 25 is released from pressure the rod will be carried upward by the spring 27, the zinc element will be carried out of the exciting fluid, and the cap 22^a will be carried down to the position shown in Figs. 1 and 2 over the resistance-coil and upper end of the primary wick, thus extinguishing the flame at the upper end of the said wick. The circuit is through the rod 16, the wire 36, the resistance-coil 37, and the rod 39 to the block 33, through the block to the head B, and through the head to the battery-rod 25.

Having thus described my invention, I claim as new and desire to secure by Letters Patent—

1. The combination with a lamp having an illuminating-wick and a primary wick, and a receptacle for containing an exciting fluid, said receptacle being provided with stationary carbon elements and a sliding zinc element, of a head on the cap of the receptacle, said head comprising a base, a vertical member having a longitudinal bore terminating in a chamber, and a horizontal member to which the lamp is secured, a bolt passing through the bore of the head and cap of the receptacle and securing the head to said cap, the head of the bolt being in the chamber of the head, a resistance-coil extending over the primary wick of the lamp, a wire leading from the coil to the head of the bolt, and an operating-rod secured to the sliding zinc element and extending out through the cap of the receptacle and the said head, substantially as described.

2. A lamp having an illuminating-wick and a primary wick, a receptacle for containing an exciting fluid, the receptacle being provided with stationary carbon elements and with a sliding zinc element, a head on the cap of the receptacle and formed of a base having a projecting tube, a vertical member having a longitudinal bore terminating at its upper end in a chamber, and a horizontal member supporting the lamp, a bolt securing the head to the cap of the receptacle, said bolt having an enlargement or head arranged in the said chamber, a resistance-coil extending over the primary wick of the lamp, a wire leading from the coil and secured to the en-

largegment or head of the bolt, a rod connect-
ed with the sliding zinc element, said rod
passing through the tube of the head and pro-
vided with a handle, and a spring surround-
5 ing the tube of the head and bearing against
the base of said head and the handle of the
rod, substantially as described.

3. A lamp having an illuminating-wick and
a primary wick and provided with a tubular
10 extension, a receptacle for containing an ex-
citing fluid, the receptacle being provided
with stationary carbon elements and with a
sliding zinc element, a head on the cap of the
receptacle and formed of a base having a pro-
15 jecting tube, a vertical member having a bore
terminating at its upper end in a chamber,
and a horizontal member in which the tubular
extension of the lamp is secured, a bolt
securing the head to the receptacle, said bolt
20 having an enlargement arranged in the cham-
ber of the vertical member, a resistance-coil
extending over the primary wick, a wire lead-
ing from the coil through the extension of the
lamp to the enlargement of the bolt and se-
25 cured thereto by a binding-screw, a sliding
rod secured to the sliding zinc element, said
rod passing through the said tube and pro-
vided with a handle at its upper end, a spring

surrounding the tube and bearing against the
base of the head and the handle of the rod, 30
an extinguishing-cap pivoted to the horizon-
tal member of the head, a lever-arm secured
to the pivot of the cap, and a link connecting
the lever-arm to the sliding rod, substantially
as described. 35

4. The combination with a lamp having a
closure provided with bores through which
wicks pass and with a lateral extension, of a
receptacle for containing an exciting fluid
provided with stationary carbon elements and 40
with a sliding zinc element, a head secured to
the top of the receptacle and having a hori-
zontal slotted member in which the extension
of the closure of the lamp is secured, a resist-
ance-coil extending over one of the wicks of 45
the lamp and in circuit connection with the
battery elements, and a spring-pressed rod
secured to the sliding zinc element, substan-
tially as described.

In testimony whereof I have signed my 50
name to this specification in the presence of
two subscribing witnesses.

CHARLES E. GERVAIS.
